(57) **CLAIM**

The ornamental design for a bottle, as shown and described.

DESCRIPTION

FIG. 1 is a top front-side perspective view of a bottle, showing my new design according to a first embodiment.

FIG. 2 is a front view of my new design shown in FIG. 1.

FIG. 3 is a rear view of my new design shown in FIG. 1.

FIG. 4 is a left side view of my new design shown in FIG. 1.

FIG. 5 is a right side view of my new design shown in FIG. 1.

FIG. 6 is a top view of my new design shown in FIG. 1.

FIG. 7 is a bottom view of my new design shown in FIG. 1.

FIG. 8 is a top front-side perspective view of a bottle, showing my new design according to a second embodiment.

FIG. 9 is a front view of my new design shown in FIG. 8.

FIG. 10 is a rear view of my new design shown in FIG. 8.

FIG. 11 is a left view of my new design shown in FIG. 8.

FIG. 12 is a right view of my new design shown in FIG. 8.

FIG. 13 is a top view of my new design shown in FIG. 8; and,

FIG. 14 is a bottom view of my new design shown in FIG. 8.

The broken lines in the figures illustrate the portions of the bottle that form no part of the claimed design.

The dot-dash broken lines immediately adjacent to the claimed areas in the views represent the boundaries of the design and form no part thereof.

1 Claim, 14 Drawing Sheets
